RUBBER STAMP MOUNT

Samuel M. Weissman, Chicago, Ill.

Application October 5, 1935; Serial No. 43,672

4 Claims. (Cl. 101—405)

This invention relates to improvements in rubber stamp mounts and it consists of the matters hereinafter described and more particularly pointed out in the appended claims.

5 The stamp mounts with which the invention is more particularly concerned, are of the kind wherein one or more surfaces of the furniture or base block is enclosed in a sheathing of relatively thin material, usually sheet metal. As heretofore, 10 made, oftentimes the base block would dry out and shrink away from the sheathing so that the latter becomes loose and due to the rough handling rubber stamps usually receive in use, is liable to displacement. Again in such stamps, difficulty is 15 encountered in properly securing the index label to the desired surface of the mount, because when the sheathing became loose, in certain instances the label would become displaced and lost.

One of the objects of the present invention is 20 to provide a rubber stamp mount structure, which eliminates the objections above noted and which at the same time, may be made at a lower cost.

A further object of the invention is to provide a stamp mount wherein the base block sheathing 25 which covers or encloses the top surface and the two side surfaces of the mount, has integral parts formed to provide a pair of longitudinal hook flanges for one of said surfaces, which defines a groove to receive the customary index label.

30 A further object of the invention is to provide a cheaper, better and more permanent stamp mount structure wherein the sheathing encloses the top surface and side surfaces of the base block and has a turned under hook engagement 35 with flanges along the bottom surface whereby the sheathing is prevented from becoming loose in the drying out of the base block, when the latter is made of wood.

The above mentioned objects of the invention, 40 as well as others, together with the advantages thereof, will more fully appear as I proceed with my specification.

In the drawing:

Fig. 1 is a perspective view of the invention as 45 embodied in a so-called mount strip style of rubber stamp.

Fig. 2 is a view in end elevation on an enlarged scale of the structure shown in Fig. 1.

Fig. 3 is a perspective view of the invention as 50 embodied in a so-called molding strip style of rubber stamp.

Referring now in detail to that embodiment of the invention illustrated in Figs. 1 and 2 respectively of the accompanying drawing, 5 indicates 55 as a whole the base block or "furniture" of the

mount as it is sometimes called. This base block, which is made of any material suitable for the purpose, as for instance wood, is of a generally rectangular cross-section and is of a length according to the size of the rubber stamp to be made. In the bottom of the base block is a longitudinal groove 6 defined at its sides by a pair of bottom shoulders or flanges 7—7.

In the groove 6 is secured a cushion 6^x which carries a die 6^y. This cushion is usually made of sponge rubber and the die which is made of rubber is formed to produce the impression desired. Usually the cushion is cemented to the base block and the die is cemented to the cushion. If desired, the cushion may be omitted and the die 15 cemented directly to the bottom of the base block.

As herein shown, the top surface, the two side surfaces and the shoulders or flanges of the base block are enclosed in a sheathing of sheet material 8, such as a suitable sheet metal. This sheathing 20 includes a top wall 9 and the side walls 10—11 respectively, the bottom marginal portions of the side walls being turned under and upwardly to form hook flanges 12 to enclose the shoulders or flanges 7 of the base block. To provide a better 25 engagement for the sheathing with respect to the base block, the top surface and the two side surfaces thereof are slightly bowed and the associated corners are rounded as shown.

In the so-called mount strip type or style of 30 rubber stamp, the same is usually provided with a handle 13. Such a handle is centrally located with respect to the top of the base block and includes a bottom extension stud 14 having a snug fit in a recess 15 in the top surface of the base 35 block. Of course, a suitable hole is provided in the top wall of the sheathing to accommodate the stud 14.

Usually in stamps of this kind, an index label 40 is carried thereby to visibly show the impression made by the stamp. As shown in Figs. 1 and 2, this index label is disposed at one side of the base although it may be disposed on the top of the base block. As shown herein, longitudinal portions of the side wall 11 of the sheathing are 45 doubled and folded over to form hook-like flanges 16—16 which face each other, the inner surfaces of said flanges being spaced outwardly from that part of the sheathing wall between them, as best appears in Fig. 2 to provide an undercut index 50 or indicia-carrying label receiving groove 17.

The index label usually constitutes an inner sheet of paper 18 bearing the impression and an outer protective sheet of transparent material 19 such as celluloid, adhered to said paper. The 55

index label is of a length equal to that of the base block and is of such width that its longitudinal margins will engage under and be held in position by the hook flanges.

5 In Fig. 3 is illustrated a modified form of structure wherein a relatively high base block is employed to provide the handle for the stamp mounting. Such a stamp is known in the trade as a "moulding" type of stamp, includes a base block 5^a of wood or other suitable substance having a die cushion receiving groove 6^a in its bottom defined at its sides by the shoulders 7^a—7^a as before. The sides of the block are curved inwardly and the top of the block is inclined downwardly toward one side of the block. The sides and top of the block, as well as the flanges or shoulders 7^a—7^a are enclosed in a sheathing of sheet material 8^a such as a suitable sheet metal. This sheathing includes a top wall 9^a and side walls 10^a and 11^a respectively, the bottom marginal portion of the side walls being turned under and upwardly to form hook flanges 12^a to enclose the flanges or shoulders 7^a.

25 In this style of rubber stamp, no handle is employed and the index label is usually carried on the top surface thereof. To meet this condition, longitudinal portions of the top wall 9^a of the sheathing are doubled and folded over to form hook-like flanges 16^a—16^a which face each other. 30 The inner surfaces of said flanges are spaced upwardly from those parts of the sheathing wall between them to provide an undercut label receiving groove 17^a. As before, the index label includes an inner sheet 18^a bearing the impression 35 and an outer transparent protective sheet 19^a of celluloid. The index label is of a length equal to that of the base block and is of such width that the margins will engage under and be held in position by the hook flanges 16^a.

40 By the construction described, the sheathing which is made from one piece of material, has integral parts formed to provide the hook flanges to hold the margins of the label. Also, due to this one piece sheathing construction, no edge 45 parts thereof are exposed to engage any object with which the stamp comes in contact, so as to loosen the sheathing. Again, even though the base block be made of wood, which may dry out, no part of the sheathing can loosen up therefrom.

50 While the groove construction for receiving the index or indicia-carrying label is shown as being formed on one side of the stamp mount, it will be understood that the same may be formed on 55 the top or opposite side or on any or all thereof, if desired.

Again, while in describing the invention, I have referred in detail to the form, arrangement and construction of the various parts of the mount, the same is to be considered only in its illustrative sense so that I do not wish to be limited thereto except as may be specifically set forth in the appended claims. 5

I claim as my invention:—

1. A rubber stamp mount embodying therein a base block having top, bottom and side surfaces, 10 and a single piece of sheet material secured to said block and providing a protective sheathing for a plurality of said surfaces, integral parts of said sheet material between its margins being doubled and folded over to provide spaced flanges 15 associated with at least one of said surface to form an undercut groove to receive a label.

2. A rubber stamp mount embodying therein a base block having top, bottom and side surfaces, the bottom surface having shoulders along each 20 side to define a die receiving groove, a single piece of thin sheet metal sheathing extending about the top surface and the two side surfaces and having a hook connection with said shoulders, a part of said thin sheet metal sheathing between 25 its margins and associated with at least one of said last mentioned surfaces, having portions folded and bent over double upon themselves to provide a pair of inwardly facing hook flanges adapted to receive and confine marginally the 30 parts of a label.

3. A rubber stamp mount embodying therein a base block having top, bottom and side surfaces, one of said surfaces being curved transversely, a thin sheet metal sheathing bent about said 35 block and covering said transversely curved surface, portions of said sheathing between its margins and associated with said transverse curved surface being folded and bent over double upon themselves to form inwardly facing hook flanges 40 that overhang that part of the sheathing between them and coat therewith in forming an undercut groove to receive a label.

4. A rubber stamp mount embodying therein a base block having top and side surfaces all of 45 which are curved transversely, a single piece of thin sheet metal sheathing covering said surfaces, portions of the sheathing associated with one of said surfaces being folded and bent over double upon themselves to form inwardly facing hook 50 flanges that overhang that part of the sheathing between them and coat therewith in forming an undercut groove to receive a label.

SAMUEL M. WEISSMAN. 55
